FIG. 1 is a perspective view of a sculpture or the like showing my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof;

FIG. 8 is a perspective view of a sculpture or the like showing a modified form of my new design;

FIG. 9 is a front elevational view thereof;

FIG. 10 is a top plan view thereof;

FIG. 11 is a left side elevational view thereof;

FIG. 12 is a right side elevational view thereof;

FIG. 13 is a rear elevational view thereof; and

FIG. 14 is a front elevational view of a sculpture or the like showing a third embodiment of my new design in which all of the surfaces are smooth.

I claim:

The ornamental design for a sculpture or the like, as shown and described.
